UNITED STATES PATENT OFFICE

JAMES VAVORIES, OF BURDINE, KENTUCKY

RAIL TIE AND FASTENING MEANS

Application filed October 4, 1928. Serial No. 310,413.

This invention relates to an improved rail tie, and rail fastening structure, which is especially, but not necessarily, adapted for use in mines, where light-weight structures of this class are provided.

One feature of the invention is the rail tie construction which is characterized by a longitudinal central portion having an upstanding central rib forming a pair of spaced open-ended channels, the outer walls of which carry horizontal extensions and flanges for secure anchorage.

An equally important feature of the invention is based upon the fact that in the usual construction in mine railways, an additional or supplemental retaining rail is disposed alongside of the main rail, the ball portion of the additional rail being engaged with the web portion of the main rail, and it is therefore a primary object of this invention to provide suitable retaining devices for holding the main and additional rails in assembled relation when so disposed in the manner mentioned.

Another very important object of the invention is to provide a dependable connection of the rails when so positioned with the tie upon which the rails are supported.

Other features and advantages of the invention will become more readily apparent from the following description and drawings.

In the drawings:—

Figure 1 is a top plan view of the rail tie and the retaining clips or clamps carried thereby.

Fig. 2 is a side elevational view of the same.

Fig. 3 is a cross section taken approximately upon the plane of the line 3—3 of Fig. 1.

Figure 4 is a fragmentary side elevation at one end of the tie and illustrating the manner in which the rails are engaged with the main rail in accordance with the invention.

The construction of the tie can better be seen in Fig. 3, wherein it will be observed that it is preferably constructed of sheet metal of appropriate texture formed to provide a central portion 5 including centralized rib 6 forming on opposite sides thereof, lon-

gitudinal open-ended channels 7. The side walls 8 of the channel carry horizontal outstanding flanges 9. This renders the construction light in weight, yet permits it to be securely anchored in the ground.

Attention is next invited to Fig. 4 wherein it will be observed that the main rail is designated by the reference character 10. This is primarily held in place by a retaining clamp 11, fastened to the tie and the base flange of the rail.

The retaining clamp 11 is formed somewhat in the nature of an elongated plate and is disposed transversely of the tie and secured thereto by means of retaining bolts 11', or in any other suitable manner. The inner longitudinal edge of the plate is somewhat offset so as to provide the portion 11" adapted to overlie and engage the base flange of the main rail, as clearly illustrated in Figure 4. The portion 11" of the clamp 11, as will be noted, overlaps the outer base flange 22, of the main rail 10, while a clamp designated generally as at 12, is provided for engaging the inner flange 23 of the said main rail in a manner to be hereinafter more fully set forth.

Each of the inner clamps 12 is bolted between its ends as at 13, one to each of the flanges 9 of the tie and the said clamps 12 are provided at their inner ends with an offset grip 14 which is adapted to overlie the base flange 23, of the main rail. The outer end of each of these clips is bent upwardly and inwardly to provide the portion 15 to permit the same to be hammered, since it is to be understood that the clamp 12 is in place, prior to the insertion of the rail 10, between the respective clamp 12 and the retaining clamp 11. Thus it is necessary that the inner clamp 12 be somewhat loosely bolted in place so that the same may be turned by suitable force applied to the portion 15 to place the clamp in a suitable retaining position with respect to the flange of the rail 10.

As in the usual construction of mine railways an additional rail 16 is provided, which rail is turned sideways so that the ball or tread portion thereof designated as at 17 will engage with the web of the main rail and the main flange portion 18 of the addi-

tional rail 16 adapted to rest upon the tie and upon the flange of the rail opposite to the flange upon which the inner clamp 12 may be secured. To retain the additional rail 16 in this position and at the tread portion 17 thereof, it will be held in constant engagement with the web of the main rail, and an additional clamp 19 is secured to the opposite flange 9 of the tie as at 24, in substantially the same manner as the inner clamp 12 is fastened to its respective clamps. Each of the clamps 19 is provided on one end with an offset lip 20 adapted to engage the base flange 18, of the rail 16, and a hammering portion 21 provided on its opposite end, said hammering portion 21 being provided by bending said end upwardly and inwardly as illustrated. The retaining clamps 19 are also adapted to be placed in position prior to the placing of the additional rail 16 in its position and the said clamp 19 is adapted to be actuated for engaging the said rail 16, in a manner similar to that employed for urging the clamps 12 in their respective engagements with the main rail 10. Of course it is to be understood that the additional retaining clamps 19 are positioned on their respective flanges of the tie, somewhat rearwardly of the retaining clamps 12, as clearly illustrated in Figure 1.

From the foregoing description and drawings, it will be seen that I have endeavored and succeeded in providing a novel contribution to the art of rails, ties, and fastening constructions.

It is thought however, that by considering the description in connection with the drawings, a clear understanding of the construction, method of use, and advantages of the invention will be had. Therefore, a more lengthy description is regarded unnecessary.

Minor changes in shape, size, and rearrangement of parts, coming within the field of invention claimed, may be resorted to if desired.

Having thus described my invention, what I claim as new is:—

1. In a structure of the class described, the combination of a rail tie, an outer abutment clamp rigidly fastened to said tie adapted for engaging the outer flange of the base of a rail supported on the tie, a second retaining clamp secured to the tie adjacent one longitudinal edge of the tie and adapted to engage the inner flange of the base of a rail, and a third retaining clamp secured to the tie adjacent the opposite longitudinal edge of the tie and adapted for engagement with the base flange of an extension rail for maintaining the tread of the extension rail in abutting relation with the first rail.

2. In a structure of the class described, in combination, a rail tie, an elongated retaining clamp extending transversely of the rail at one end of the tie, said clamp being offset

along one longitudinal edge thereof and adapted to overlie the outer flange of a rail supported on the tie, a second clamp secured to the tie adjacent one longitudinal edge of the tie, and said second clamp being provided with an offset portion adapted to engage the inner base flange of the tie, and a third retaining clamp secured to the tie adjacent its opposite longitudinal edge, and said last mentioned clamp being offset at one end and having its offset portion adapted to engage the base flange of an extension rail for maintaining the extension rail in wedged relation to the first rail.

3. In a structure of the class described, the combination of a rail supporting means comprising a body provided with a central longitudinally extending anchoring portion and a longitudinally extending rib within the anchoring portion forming a pair of open sided channels on opposite sides thereof, together with a pair of horizontal outstanding rail supporting flanges carried by the upper portion of the other side walls of said channels, a rail engaging clamp carried by the flanges of the body and bringing said channels, and the said central rib providing a supporting surface for the intermediate portion of the rail engaging clamp.

4. In a structure of the class described, the combination of a rail supporting means comprising a body provided with a central longitudinally extending anchoring portion and a longitudinally extending rib within the anchoring portion forming a pair of open sided channels on opposite sides thereof, together with a pair of horizontal outstanding rail supporting flanges carried by the upper portion of the other side walls of said channels, a rail engaging clamp carried by the flanges of the body and bridging said channels, and the said central rib providing a supporting surface for the intermediate portion of the rail engaging clamp, and a rail engaging clamp carried by each of said flanges, the supporting clamp on one of said flanges extending forwardly of the other of said clamps and cooperating with the first mentioned rail engaging clamp for holding a rail in position upon the said support, and the other of the last mentioned rail engaging clamps adapted to engage an extension rail in wedged relation to the first rail.

In testimony whereof I affix my signature.

JAMES VAVORIES.
